[57] **CLAIM**

The ornamental design for a reversible seat for a bathtub or the like, as shown and described.

DESCRIPTION

FIG. 1 is a perspective view of a reversible seat for a bathtub or the like showing my new design;

FIG. 2 is a top plan view thereof, the bottom being a mirror image of the top shown;

FIG. 3 is a rear elevational view thereof;

FIG. 4 is a front elevational view thereof;

FIG. 5 is a left side elevational view thereof; and

FIG. 6 is a right side elevational view thereof.

The fragmentary broken line representation of a combined bathtub and shower enclosure in FIG. 1 is for purposes of illustration only.
